CLAIM

The ornamental design for an combined electric toothbrush with water flosser as shown and described.

DESCRIPTION

FIG. 1 is a perspective view of an combined electric toothbrush with water flosser showing my new design;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is an exploded perspective view of the combined electric toothbrush with water flosser.

The broken lines in the drawings depict portions of the combined electric toothbrush with water flosser that form no part of the claimed design.

1 Claim, 9 Drawing Sheets
